UNITED STATES PATENT OFFICE.

JOHN F. HARDY, OF MONTICELLO, INDIANA.

HYDROCARBON-BURNER.

SPECIFICATION forming part of Letters Patent No. 700,914, dated May 27, 1902.

Application filed October 15, 1900. Serial No. 33,091. (No model.)

To all whom it may concern:

Be it known that I, JOHN F. HARDY, of Monticello, in the county of White and State of Indiana, have invented certain new and useful 5 Improvements in Hydrocarbon-Burners; and I do hereby declare that the following is a full, clear, and exact description thereof, reference being had to the accompanying drawings, and to the letters of reference marked thereon, 10 which form a part of this specification.

This invention relates to improvements in hydrocarbon-burners of that class in which the flame of the admixture of the hydrocarbon vapor and air is directed against a reticulated tube of refractory material to heat 15 the same to incandescence.

Certain of the features of the invention may, however, be used with burners for different purposes.

20 The invention consists in the matters hereinafter set forth, and more particularly pointed out in the appended claims.

Figure 1 is a fragmentary vertical section of a burner made in accordance with my invention, taken on line 1 1 of Fig. 2. Fig. 2 is a cross-section on line 2 2 of Fig. 1. Fig. 3 is a vertical section on line 3 3 of Fig. 1 with parts shown in elevation. Fig. 4 is a vertical section on line 4 4 of Fig. 2 with parts shown 25 in sections. Fig. 5 is a horizontal section on line 5 5 of Fig. 3, showing parts in elevation. Fig. 6 is a detached view showing a closure for closing an opening in the jacket depending from the burner-body.

30 As shown in the drawings, A designates the body of the burner, embracing a disk-like part and a hollow shell or casing A' of less diameter than the disk and provided with a depending flange or jacket A², concentric with and herein shown as made separate from and attached to the body by screws. Said casing A' is made of such size as to receive the usual gallery which supports the refractory mantle and the lamp-chimney. Said body portion is 35 provided on its under side with two openings A³ A⁴, which are screw-threaded to receive, respectively, an annular fitting B, to which is attached the fixture supply-pipe C, and an angular injector-pipe consisting of a vertical 40 part D and a horizontal part D', on which latter is formed a vertically-arranged tubular part or sleeve E and at the upper end of which

sleeve is located a jet-nozzle e, from which issues the superheated vaporized or gaseous hydrocarbon after having passed through the 55 various vaporizing and superheated passages to be hereinafter described. The bore of the horizontal part of the injector-tube D' is provided with a valve-stem D², provided on its inner end with a conical valve d, adapted to 60 engage a similarly-shaped valve-seat in said passage and by which the supply of the generated gas or vapor is controlled to the nozzle e. The nozzle e is adapted to be cleaned by a cleaning-needle e', which is attached to a 65 rotative endwise-movable shaft E², which has screw-threaded engagement with the bore of the sleeve or tubular part E and provided at its lower end with a disk or wheel to rotate the same. Said sleeve E is herein shown as 70 formed integral with the horizontal part of the injector-tube and with the passage therein communicating with the passage of said injector-tube. Said horizontal part of the injector-tube passes across the burner at one 75 side of the central axis thereof, and the nozzle e is located concentrically with respect to the central axis of the burner.

F designates a tube depending from the body A, said tube being screw-threaded at its 80 upper end and engaging a screw-threaded opening in said body and projecting at said screw-threaded end through the body. Said tube F and the interior of the shell A' constitute the mixing-chamber of the burner, and 85 the lower end of the tube F is located above the jet-nozzle e to receive the gaseous hydrocarbon fuel from said nozzle. The opening in the body through which the tube F passes is herein shown as located at one side of the 90 central axis of the burner, and the tube F is therefore disposed obliquely with respect to said axis, as clearly shown in Figs. 3 and 4.

The opening A³ communicates with an upwardly-opening passage a', formed in the wall 95 of the shell or casing A', which passage is closed at its upper end. Similarly the opening A⁴ communicates with an upwardly-directed passage a², formed in the wall of the shell or casing A', closely adjacent to the opening a', 100 and which passage a² is closed at its upper end. Said passages a' a² are connected near their lower ends by means of an obliquely-disposed connecting-passage a³, drilled in the

wall of the shell A'. When said passages are located closely adjacent to each other, as shown herein, the part of the wall of the casting containing the same is thickened, so that 5 the opening in said shell or casing is somewhat eccentric to the central axis of the burner. The passages may, however, be formed outside of or partially outside the walls of the shell.

10 G designates a small tube which has screw-threaded connection at its lower end with the end of the supply-tube B which enters the passage a', and H designates a similar tube located in the passage a² and having screw-threaded connection at its lower end with the 15 part of the injector-tube which enters the opening A⁴. Said passages a' and a² are formed to provide a conduit outside the tubes for the passage of the fuel fluid therein. In this instance the tubes G and H are made of such 20 diameter as to provide annular passage-ways or conduits surrounding said tubes; but such conduits may be otherwise formed. The tubes terminate short of the upper ends of the passages a' a², so that said conduits have open 25 communication with the bores of the tubes. The tubes G and H form, in effect, continuations of the supply-tube and injector-tubes, respectively, and may, if desired, be made 30 integral therewith.

I designates a screen which extends across the upper open end of the shell or casing A' and rests at its edges upon an annular shoulder or rabbet a⁴, formed on the inner surface 35 of said casing. Said screen serves the usual purposes of a guard to prevent the flame passing downwardly into the burner, as usual in devices of this character. In order to hold the screen in place, it is made of concavo-con- 40 vex form and is made of such size as to spring into place and held therein by its resiliency.

J designates an initial heating-cup which surrounds the lower end of the sleeve or tubular part E and arranged concentrically with 45 respect to the axis of the burner. Said cup is of a diameter equal to the depending flange or jacket A² and is preferably made of sheet metal and pressed tightly against the stuffing-box e² at the lower end of said sleeve or 50 tubular part E and is thereby held in place. Said initial heating-cup is adapted to contain a burning fluid, which is ignited to heat the horizontal arm of the injector-tube in starting the burner, as is usual in this class 55 of burners. A space is left between the upper edge of the heating-cup J and the lower edge of the jacket A² of the body to permit entrance of air to the mixing-chamber.

I have provided a novel form of wick K, 60 which is located in the initial heating-cup to absorb a burning liquid placed within the cup, such as alcohol or the like, and designed to present a maximum area of the burning liquid to the action of the air. The wick in 65 this instance consists of a wire which is covered with an absorbent material of practically an indestructible character, such as as-

bestos. After the wire has been covered with such material it is wound in spiral form and afterward bent in the form of a ring, as shown 70 in Fig. 5, so as to surround the sleeve E. The asbestos absorbs the liquid with which it comes in contact, and the spiral form of the wick is such as to present a maximum amount of surface to the action of the air, so that the 75 liquid will burn freely.

In the operation of the burner and after the mixture has been ignited at the upper end of said shell the liquid hydrocarbon passes from the supply-pipe C through the angular fitting 80 B into the lower end of the tube G and passes upwardly therethrough and escapes at the upper end of said tube into the conduit surrounding the tube. The upper part of said passage a' being located immediately subjacent to the flame becomes highly heated, so that the liquid hydrocarbon is vaporized in the upper end of said tube and the upper end of the conduit, and the resultant vapor passes downwardly through said conduit and 85 through the connecting - passage a³ at the lower end thereof to the conduit surrounding the tube H, connected with the injector-tube. The vaporized fuel passes upwardly through said passage a² and at the upper end thereof 90 becomes superheated and enters the upper end of the tube H, through which it passes downwardly into the injector-tube and from whence it is discharged into the mixing-chamber. The passage in the tube G and the surrounding conduit may be termed the "primary" passage, while the passage in the tube H and the surrounding conduit may be termed 95 the "secondary" passage.

In the operation of the burner all or the 100 greater part of the vaporization of the hydrocarbon fuel will take place in the tube G, so that the remaining parts of the primary and secondary passages will be devoted to heating and superheating the gasified fuel. It 105 will be observed that by reason of the peculiar arrangement of said passages the total or aggregate length of the primary and secondary passages is equal to about four times the length of either of the passages a' a², thereby 110 providing an enormous heating-surface for the effective heating of the gasified fuel. In order to further increase the radiating-surfaces of the passages a' a², the same are provided with roughened inner walls, such roughening of the walls being herein shown as effected by providing said passages with interior screw-threads. It will be observed, furthermore, that the liquid fuel enters the 115 burner through the interior of the tube G and is vaporized before or at the point of issuing from said tube, so that the vaporized fuel is subjected to a much larger heating-surface, consisting of the walls of the passage a', than if the arrangement were reversed and the 120 liquid fuel entered the passage a' and the vapor generated therefrom were returned through the passage in the tube G. In the latter case the tube G being surrounded by 125

the relatively cool liquid fuel entering the passage a' the vaporized fuel would in its return passage through said tube lose a considerable portion of its heat by reason of the 5 comparative insulation of the tube G from the heated parts of the burner, with the result of a less effective heating of the gaseous fuel. Furthermore, it will be observed that the passage a' terminates above the point of 10 entrance of the liquid fuel into the tube G, so that the liquid when it reaches the level of the lower end of the passage a' will have become to an extent heated, and said incoming liquid fuel will not to any appreciable extent absorb heat from the already-heated vaporized fuel passing downwardly through the conduit in the passage a' .

The jacket A² is slipped downwardly over the body A and is provided with a downwardly-opening vertical slot a^5 , which passes over the supply-tube fitting B. Means are provided for closing said slot, consisting of a plate L, curved in cross-section to conform to the curvature of the jacket and provided 25 with an opening at its upper end by which it may be suspended from the fitting B, said opening being made of such size as to be slipped over the inner end of said fitting before the same is attached to the burner-body. 30 The plate is made of a width to overlap the margins of the jacket-wall on each side of the slot. Said fitting is provided outside the plate with a protuberance B', which engages the plate in such manner as to hold the 35 same in place to cover said slot. As herein shown, the inner surface of said protuberance is made conical, so that the weight of the plate maintains the same in engagement with the smaller part of the cone and in position to close the slot. The slot is opened by 40 swinging the plate upwardly, and the hole in the plate is made of such size as to permit it to ride over the larger part of the cone, the curved shape of the plate and jacket causing 45 the plate to be pushed laterally outwardly over the cone when the plate is thrown upwardly. When the plate is released, the weight thereof co-operates with the cone and causes the plate to slide inwardly to its closing 50 position. If desired, the protuberance B' may be so formed as not to permit the plate to be moved laterally outwardly, in which event the plate will be made of a resilient material, so that when swung upwardly the part containing 55 the opening will flatten somewhat, and when moved downwardly into its closing position the resiliency of the plate will cause the same to resume its curved cross-section, so that it will fit closely over the wall of the 60 jacket containing the slot. The slot or opening a^5 in the construction illustrated is provided for two reasons—namely, to permit the jacket to be slipped downwardly over the supply-pipe fitting B and to afford means for 65 gaining easy access to the nozzle or other parts of the burner to clean the same. The closure is provided to prevent lateral drafts

entering the jacket and to give a finished appearance thereto. In case the supply-pipe be otherwise connected with the burner and 70 does not pass through the jacket the plate may be suspended from a suitable support located over the slot.

I claim as my invention—

1. A hydrocarbon-burner comprising a body 75 portion provided with a mixing-chamber, a supply-pipe and an injector-tube, the latter discharging into the mixing-chamber, said body portion embracing a rising shell which surrounds the upper part of the mixing-chamber, the wall of said shell being provided with 80 a passage which extends at its upper end near the point of combustion and communicates with the injector-tube, and said supply-pipe having a tubular part which enters a 85 second passage in the wall of said shell and terminates adjacent to the point of combustion of the burner, said second passage being constructed to provide outside of the tubular part a conduit which communicates with the 90 first-mentioned passage and therethrough with the injector-tube, and the tubular part communicating at its upper end with said conduit, said supply-pipe fitting detachably within an opening in the body portion, and the 95 tubular part being connected with the supply-pipe so as to be removable therewith from the body portion.

2. A hydrocarbon-burner comprising a body portion provided with a centrally-located 100 mixing-chamber, a supply-pipe and an injector-tube, the latter discharging into the mixing-chamber, said supply-pipe having a tubular part which enters a vertical passage formed 105 in the wall of the mixing-chamber and terminating adjacent to the point of combustion of the burner, said passage being constructed to provide outside the tubular part a conduit which communicates with the injector-tube, the tubular part communicating at its upper 110 end with said conduit and the passage having a roughened interior to increase its radiating-surface.

3. A hydrocarbon-burner comprising a body portion provided with a mixing-chamber, a 115 supply-tube and an injector-tube, which latter discharges into said mixing-chamber, said body portion embracing a rising shell which surrounds the upper end of the mixing-chamber and said supply and injector tubes communicating 120 with each other through the medium of a tortuous vaporizing and superheating passage formed in the wall of said shell and embracing two similar parts, each consisting of an outer and an inner passage which 125 have communication with each other at the upper ends thereof and the two parts of the tortuous passage communicating with each other near the lower ends thereof through an opening formed in the body of the burner. 130

4. A hydrocarbon-burner comprising a body portion provided with a mixing-chamber, a supply-tube and an injector-tube, the latter discharging into the mixing-chamber, said

body portion embracing a rising hollow shell which surrounds the upper part of the mixing-chamber, said shell being provided in its wall with upwardly-directed passages which

- 5 terminate adjacent to the point of combustion of the burner, and the supply and injector tubes having tubular parts which enter said passages and communicate at their upper ends with conduits formed in the passages
- 10 and surrounding the tubular parts, said conduits being connected by a communicating passage.

5. A hydrocarbon-burner comprising a body portion provided with a mixing-chamber, a supply-tube and an injector-tube, which latter discharges into said mixing-chamber, said supply and injector tubes communicating with each other through the medium of a tortuous vaporizing and superheating passage, said passage embracing two similar parts, each consisting of an outer and an inner passage which have communication with each other at their upper ends, and one of which is provided with a roughened inner wall, the two parts of the tortuous passage communicating with each other near the lower ends thereof.

- 6. A hydrocarbon-burner comprising a body portion provided with a mixing-chamber, and with a passage extending at its upper end near the point of combustion, an injector-tube discharging into the mixing-chamber and communicating at its end remote from the mixing-chamber with said passage, and a supply-pipe fitting detachably within an opening in the body portion and provided with a reduced part which enters a passage in the body portion, said reduced part being connected with the supply-pipe and located in alinement therewith so as to be removable from the body portion with said pipe and communicating at its upper end near the point of combustion with said passage, and the passage communicating at its lower end with the first-mentioned passage and the injector-tube.

7. A hydrocarbon-burner comprising a body portion provided with a mixing-chamber, an injector-tube discharging into the mixing-chamber, said body being provided with a supply-passage which terminates near the point of combustion and adapted for connection with a supply-pipe, and the injector-tube being provided at its upper end with a reduced portion which enters a second elongated passage in said body and is located concentrically therein, said reduced portion communicating at its upper end near the point of combustion with said second passage, and said second passage communicating through a small connecting-passage with the supply-passage of the burner.

- 8. A hydrocarbon-burner provided with a mixing-chamber, a supply-pipe and an injector-tube, the latter discharging into the mixing-chamber, said injector-tube having a reduced part which enters a passage formed in the wall of the mixing-chamber and termi-

nates adjacent to the point of combustion of the burner, said passage being constructed to provide outside of the tubular part a conduit which communicates with the supply-pipe, the tubular part communicating at its upper end with said conduit and said passage having a roughened inner wall.

9. A hydrocarbon-burner comprising a body portion provided with a mixing-chamber, and with a passage extending at its upper end near the point of combustion, an injector-tube discharging into the mixing-chamber and communicating at its end remote from the mixing-chamber with said passage, and a supply-pipe communicating with a reduced part which enters a second passage in the body portion, said reduced part communicating at its upper end near the point of combustion with said second passage and said second passage communicating at its lower end with the first passage and therethrough with the injector-tube.

10. The combination with the body of a hydrocarbon-burner provided with an annular depending shell or jacket, which latter is provided in its wall with an opening, of a plate curved to conform to the curved surface of said jacket adapted to close said opening, said plate depending loosely from a support projecting from the jacket, whereby it is swung by its weight to its lowermost position, and means on said support acting when the plate is swung downwardly to move the same closely against the jacket-wall.

11. The combination with the body of a hydrocarbon-burner provided with an annular depending shell or jacket, which latter is provided in its wall with an opening, of a curved plate pivoted to a support projecting from the jacket, and a conical projection on the support radially outside the plate with respect to the axis of the jacket, the pivot-opening in the plate being made larger than its pivot-support inside said conical projection whereby, when the plate is swung upwardly, the pivoted end thereof moves upwardly and outwardly over said conical projection, said plate when relieved swinging downwardly by gravity into its closing position, and the conical projection causing the plate to be moved inwardly against the jacket-wall.

12. The combination with the body of a hydrocarbon-burner provided with a supply-pipe, and a flange or jacket depending from the body, which latter is provided with a slot to pass over said supply-pipe, of a plate depending loosely from said supply-pipe adapted to cover said slot and curved to correspond to the outer curved surface of said flange or jacket, said plate being free to swing to its lowermost position by its own weight when released, and means on said support acting when the plate is swung downwardly to move the plate closely against said jacket.

13. A hydrocarbon-burner comprising a body portion provided with a mixing-chamber, a supply-tube and an injector-tube con-

nected with vaporizing and superheating passages in said body portion, said injector-tube discharging into the mixing-chamber, an auxiliary heating-cup located below the said injector-tube and provided with a wick comprising a wire covered with an absorbent material and coiled in spiral form.

14. A wick for the purpose set forth and comprising a wire covered with an absorbent material and coiled in spiral form.

15. A wick for the purpose set forth com-

prising a wire covered with an absorbent material, said wick being coiled in spiral form and shaped into a ring.

In testimony that I claim the foregoing as my invention I affix my signature, in presence of two witnesses, this 10th day of October, A. D. 1900.

JOHN F. HARDY.
